UNITED STATES PATENT OFFICE

CHARLES C. MILLER, OF FORT WAYNE, INDIANA

BOX

Application filed June 28, 1928. Serial No. 288,876.

This invention relates to boxes and has special reference to a folding paper box wherein the bottom or body portion is folded from a flat unitary blank while the cover or 5 top portion is folded from a second flat unitary blank of like character and of suitable size to fit over the first.

In my prior application, copending here-
with, which was filed on August 16, 1926
10 and bears the Serial Number 129,351 I have
disclosed a form of folding paper box de-
signed to be packed with the side portions
folded inward on the body and end flaps fold-
ed over these side portions for storage in
15 shipment, the box being of such character
that upon lifting the box and bending the end
walls upward the corner pieces automatically
fold in, this being accomplished by initially
weakening certain of the fold lines to a great-
20 er extent than others. In this box I have
found it necessary to make, on each corner
piece, a diagonal fold line as is quite common
in boxes of this description. I have discov-
ered that if this diagonal fold line is so made
25 as to divide the corner members into equal
parts then when the box is folded there is a
tendency for the side walls to bulge slightly
outward at the corners. In many types of
30 boxes this bulging of the side walls at these
points is objectionable as not producing the
neat appearance that is obtained with a box
built to shape in the factory. I have further
discovered that the bulging may be overcome
35 by so arranging the angle of the diagonal
fold line that the angle between this diagonal
fold line and the fold line between the corner
and side wall portion of the box is slightly
less than the angle between the diagonal fold
40 line and the fold line between the corner por-
tion and the end wall of the box. With a box
constructed in this manner the box, when
folded, presents an appearance at the corner
that is practically that of a factory finished
45 box as there is no bulging of the side wall por-
tions.

In my prior application in the formation of
the blank I so weaken the fold lines that the
fold line between the corner member and the
end wall portion was weaker than the fold
50 line between such corner member and the side

wall portion and I accomplish this by creasing
the box longitudinally and transversely with
equal creases and also perforating the mate-
rial at the creased line between each corner
piece and end wall portion. In the class of 55
boxes in which the corners are required to
present a very neat appearance I have found
that perforating the box in this manner tends
to produce a roughness at the corners and is
objectionable to many users on this account. 60
I have now found that the same effect may be
produced by increasing the breaking down
of the longitudinal creases at the ends thereof
where they extend between the corner mem-
bers and end wall portions and that when a 65
box is made in this manner the tendency to
break and become rough at this joint or fold
is obviated and when taken in connection
with the particular arrangement of the diag-
onal fold line on the corner piece greatly im- 70
proves the appearance of the box and renders
it much more salable.

I have also found that the perforations,
which I formerly used in the diagonal fold
lines of the corner members sometimes caused
breaking of these corner members at this
point when the box was folded and conse- 75
quent loss of such box. I have now found
that this can be overcome by creasing the out-
er end of the diagonal fold line while perfo-
rating the inner end and that when this is
done the creased outer portion will prevent 80
parting of the two portions of the corner
member along the diagonal fold line while the
perforations of the inner part will effectually
weaken this diagonal fold line so that the
blank will fold as readily along this diagonal 85
fold line as it will fold on the line between
the corner member and end wall portion.

The objects of the present invention are, 90
therefore, to provide an improved corner
member construction and a blank for folding
boxes embodying this construction wherein
the corner members will be provided each
with a diagonal fold line and a fold line be- 95
tween such corner member and end wall por-
tion of substantially equal strength and so
arranged that the box, when folded, will pre-
sent a neat square corner with the parts flush
with each other and perfectly smooth on the 100

exterior, the diagonal fold line of the corner member being so constructed as to make the member easy to fold on this line without danger of severing.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a plan view of a box blank constructed in accordance with this invention.

Figure 2 is a plan view of this blank folded for shipping and storing.

Figure 3 is an enlarged detail view in plan of one corner of the box.

Figure 4 is a section on the line 4—4 of Figure 3.

Figure 5 is a section on line 5—5 of Figure 3.

Figure 6 is a section on the line 6—6 of Figure 3.

Figure 7 is an enlarged and exaggerated section on the line 7—7 of Figure 3 showing the weakening of the fold between the corner member and end wall portion of the box.

Figure 8 is a section on each of the lines 8—8 of Figure 3 showing the normal creasing exaggerated of the remaining rectangular fold lines.

Figure 9 is a section on a horizontal plane taken through one corner of the box as set up and disclosing the square end flush arrangement of the parts at such corner.

In the present embodiment of the invention there has been disclosed one part of a folding box, the top and bottom being both alike. For the purpose of convenience in description we will regard this part as the bottom of the box and it will be seen that this box is formed from a blank of foldable material such as millboard, pasteboard or the like and consists of a rectangular body portion 10 which has at each side a side wall portion 11 defined from the body portion by a weakened fold line 12 which is preferably produced by creasing down the material in longitudinal lines extending throughout the length of the sides of this box portion and across the ends of end wall portions 13 as at 14.

These end wall portions are similarly defined from the body portion by fold lines 15 which extend across the ends of the side wall portions as at 16 so that the extensions 14 and 16 define two sides of quadrangular corner members each having a diagonal fold line wherein the outer portion 17 is formed by breaking down or creasing the material while the inner portion 18 is formed by perforations.

It will be noted that the angle between the

diagonal fold line 17, 18 and the fold line 16 is less than the angle between said diagonal fold line and the fold line 14 so that the free edge portion 19 of the corner member is shorter than the free edge portion 20 of each corner member. By this means when the corner member is folded the slightly great length of the part 20 ensures that the side wall 11 will not bulge out at the top of the corner but will be held truly perpendicular with relation to the bottom 10. It must be understood, of course, that this difference in length between the edges 20 and 19 is not great. For instance, in a blank wherein the side and end walls are about two and a half inches high the difference in these lengths is only about one-sixteenth of an inch but it is important, in fact very important, that this difference exists in order to have the side walls perpendicular to the bottom or body 85 of the blank.

It is further to be noted that the breaking down or creasing of the portions 14 of the longitudinal fold lines is greater than that accomplished on the portions 12 of these fold lines and also greater than that accomplished at the fold lines 15 and 16 so that this breaking down effect renders the fold lines 14 weaker than the fold lines 16. Now, under these circumstances when the box is packed for shipment and storage the side wall portions and corner portions are folded over on the body and end wall portions respectively as disclosed in Figure 2, the end flaps 21 which extend from the end wall portions 12 and are defined by outer fold lines 22 form such end wall portions, being folded over as also shown in that figure. The usual strips or raised portions 23, as shown in my previous application, are used to engage and hold the edges 24 of the end flaps when the box is set up. Under these conditions when the stored and folded blank is picked up by the ends and the hands pressed toward each other the side walls 11 will swing up and out and the end walls 13 be forced in. The corner portions will fold so that during all of this operation, practically from the start, the portion between each diagonal fold line and the corresponding fold line 14 will lie flat against the respective end wall portion 13 and thus permit easy folding in of the end flaps 21.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. A flat, unfolded blank for folding boxes including a rectangular body portion, side wall portions at the sides of the body and defined therefrom by weakened fold lines, end wall portions at the ends of the body and defined therefrom by weakened fold lines, and corner members at the corners between the side and end wall portions and defined from said side and end wall portions by weakened fold lines, said corner members each having a weakened diagonal fold line extending outwardly from the respective corner of the body and in a direction such that the angle between the diagonal fold line and the fold line defining the corner from the end wall is greater than the angle between said diagonal fold line and the fold line defining the corner from the side wall, each fold line between a respective corner and end wall being imperforate but initially broken down to a greater extent than the fold lines between the corners and side walls to produce more ready flexure between the corners and end walls than between the corners and side walls.
2. A flat, unfolded blank for folding boxes including a rectangular body portion, side wall portions at the side of the body and defined therefrom by weakened fold lines, end wall portions at the ends of the body and defined therefrom by weakened fold lines, and corner members at the corners between the side and end wall portions and defined from said side and end wall portions by weakened fold lines, said corner members each having a weakened diagonal fold line extending outwardly from the respective corner of the body and in a direction such that the angle between the diagonal fold line and the fold line defining the corner from the end wall is greater than the angle between said diagonal fold line and the fold line defining the corner from the side wall, said diagonal fold lines each having its outer portion imperforate and its inner portion perforated, each fold line between a respective corner and end wall being imperforate but initially broken down to a greater extent than the fold lines between the corners and side walls to produce more ready flexure between the corners and end walls than between the corners and side walls.
3. A flat, unfolded blank for folding boxes including a rectangular body portion, side wall portions at the sides of the body and defined therefrom by weakened fold lines, end wall portions at the ends of the body and defined therefrom by weakened fold lines, corner members at the corners between the side and end wall portions and defined from said side and end wall portions by weakened fold lines, and end flaps extending from the free edges of the end wall portions and de-
- fined therefrom by weakened fold lines and of substantially the same width as the end wall portions to engage the body portion when folded, said corner members each having a weakened diagonal fold line extending outwardly from the respective corner of the body and in a direction such that the angle between the diagonal fold line and the fold line defining the corner from the end wall is greater than the angle between said diagonal fold line and the fold line defining the corner from the side wall, each fold line between a respective corner and end wall being imperforate but initially broken down to a greater extent than the fold lines between the corners and side walls to produce more ready flexure between the corners and end walls than between the corners and side walls.
4. A flat, unfolded blank for folding boxes including a rectangular body portion, side wall portions at the sides of the body and defined therefrom by weakened fold lines, end wall portions at the ends of the body and defined therefrom by weakened fold lines, corner members at the corners between the side and end wall portions and defined from said side and end wall portions by weakened fold lines, and end flaps extending from the free edges of the end wall portions and defined therefrom by weakened fold lines and of substantially the same width as the end wall portions to engage the body portion when folded, said corner members each having a weakened diagonal fold line extending outwardly from the respective corner of the body and in a direction such that the angle between the diagonal fold line and the fold line defining the corner from the end wall is greater than the angle between said diagonal fold line and the fold line defining the corner from the side wall, said diagonal fold lines each having its outer portion imperforate and its inner portion perforated, each fold line between a respective corner and end wall being imperforate but initially broken down to a greater extent than the fold lines between the corners and side walls to produce more ready flexure between the corners and end walls than between the corners and side walls.
5. A flat, unfolded blank for folding boxes including a rectangular body portion, side wall portions at the ends of the body and defined therefrom by weakened fold lines, end wall portions at the ends of the body and defined therefrom by weakened fold lines, corner members at the corners between the side and end wall portions and defined from said side and end wall portions by weakened fold lines, and end flaps extending from the free edges of the end wall portions and defined therefrom by weakened fold lines and of substantially the same width as the end wall portions to engage the body portion when folded, said corner members each having a

weakened diagonal fold line extending outwardly from the respective corner of the body and in a direction such that the angle between the diagonal fold line and the fold line defining the corner from the end wall is greater than the angle between said diagonal fold line and the fold line defining the corner from the side wall, each fold line between a respective corner and end wall being imperforate but initially broken down to a greater extent than the fold lines between the corners and side walls to produce more ready flexure between the corners and end walls than between the corners and side walls, and retaining strips spaced slightly from the end walls and engageable by the edge flaps when folded.

6. A flat, unfolded blank for folding boxes including a rectangular body portion, side wall portions at the sides of the body and defined therefrom by weakened fold lines, end wall portions at the ends of the body and defined therefrom by weakened fold lines, corner members at the corners between the side and end wall portions and defined from said side and end wall portions by weakened fold lines, end flaps extending from the free edges of the end wall portions and defined therefrom by weakened fold lines and of substantially the same width as the end wall portions to engage the body portion when folded, said corner members each having a weakened diagonal fold line extending outwardly from the respective corner of the body and in a direction such that the angle between the diagonal fold line and the fold line defining the corner from the end wall is greater than the angle between said diagonal fold line and the fold line defining the corner from the side wall, said diagonal fold lines each having its outer portion imperforate and its inner portion perforated, each fold line between a respective corner and end wall being imperforate but initially broken down to a greater extent than the fold lines between the corners and side walls to produce more ready flexure between the corners and end walls than between the corners and side walls, and retaining strips spaced slightly from the end walls and engageable by the edge flaps when folded.

In testimony whereof he affixes his signature.

CHARLES C. MILLER.
